DESIGN FOR A BROOCH OR SIMILAR
ARTICLE

Irving Aberbach, New York, N. Y.

Application December 31, 1948, Serial No. 150,497

Term of patent 14 years

(Cl. D45—19)

To all whom it may concern:

Be it known that I, Irving Aberbach, a citizen of the United States and residing in the county of Bronx, city and State of New York, have invented a new, original, and ornamental Design for a Brooch or Similar Article, of which the following is a specification, reference being had to the accompanying drawings, forming part thereof and in which:

Fig. 1 is a front elevational view of a brooch or similar article, showing my new design.

Fig. 2 is a top plan view.

Fig. 3 is a left end view.

Fig. 4 is a right end view.

The essential feature of the design resides in the portion shown in the full lines.

I claim:

The ornamental design for a brooch or similar article, substantially as shown and described.

IRVING ABERBACH.
